UNITED STATES PATENT OFFICE.

HENRY A. SCHAEFER, OF ROCHESTER, NEW YORK, ASSIGNOR TO SCHAEFER & SCHLEGEL, OF SAME PLACE.

DESIGN FOR A SKIRT-PROTECTOR.

SPECIFICATION forming part of Design No. 33,403, dated October 16, 1900.

Application filed April 24, 1900. Serial No. 14,190. Term of patent 7 years.

To all whom it may concern:

Be it known that I, HENRY A. SCHAEFER, a citizen of the United States, residing in the city of Rochester, county of Monroe, and State 5 of New York, have invented and produced a new and original Design for a Skirt-Protector, of which the following is a specification, reference being had to the accompanying drawing, forming a part thereof.

10 My design embodies a skirt protector or binding embodying a strip or band of fabric having a brush or fringe upon one edge and a characteristic ornamentation extending through the body of the fabric.

15 The design illustrated in the drawing consists of a band or strip of fabric 1, upon the edge of which is a brush or fringe 2. Narrow headings 3 and 4 are arranged above the brush portion, and upon the opposite edge of the fabric and between them is a longitudinally-extending broad band or ornamentation consisting of a plurality of bars 6, each bar being composed of a plurality of minor bars. 20

I claim—

15 The design for a skirt-protector substantially as herein shown and described.

HENRY A. SCHAEFER.
